UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

TRUCK FOR ROLLING VEHICLES.

SPECIFICATION forming part of Letters Patent No. 408,083, dated July 30, 1889.

Application filed June 11, 1889. Serial No. 313,910. (No model.)

To all whom it may concern:

Be it known that I, EDWARD WILLIAM MACKENZIE HUGHES, of Chicago, Cook county, Illinois, have invented a new and useful Improvement 5 in Trucks for Rolling Vehicles, of which the following is a full, true, and exact description, reference being had to the accompanying drawings.

This invention relates to an improvement 10 in trucks for rolling vehicles unprovided with end frames and in which the side frames and transom are formed of one piece of pressed steel or other metal.

My invention will be readily understood 15 from the accompanying drawings, in which—

Figure 1 represents a plan view; Fig. 2, a vertical section through the transom, and Fig. 3 a horizontal section through Fig. 2 on the line *x x*.

20 My truck, as shown, consists of a transom A and side frames B, having pedestals C integral therewith, the whole formed of one piece of pressed steel. A suitable blank is cut and then pressed in the well-known way 25 into the shape indicated, and by reason of the fact that the transom A is integral with the side frames B no end frames are required. By preference I provide a stiffening-plate D', riveted in the open bottom of the transom A 30 and provided with suitable openings for the king-bolt, and also additional openings insuring lightness. The pedestals C are provided with cheek-pieces D riveted thereto and affording additional strength and stiffness at 35 that point.

The center plate F may be of any known

kind; but I prefer to make it of pressed steel, as I do likewise the side bearing-plates G.

It will be seen that the side frames and transom are pressed into box shape, both 40 sides of the transom and both sides of the side frames being pressed downward and substantially parallel with each other, so as to form a box-shaped structure, as indicated.

What I claim as my invention, and desire to 45 secure by Letters Patent, is—

1. A truck-frame for rolling vehicles, having the side frames and transom formed of one piece of metal, which affords the necessary strength and rigidity without the employment of end frames, substantially as described.

2. A truck for rolling vehicles, consisting of the box-shaped side frames and transom pressed from a single plate of metal, said transom affording sufficient strength and rigidity 55 without the employment of end frames, substantially as described.

3. The combination of the side frames B B, the transom A, and the stiffener D, the said 60 side frames being unprovided with end frames and relying for their support upon the transom A and stiffener D, substantially as described.

In testimony whereof I have signed my name 65 to this specification in the presence of two subscribing witnesses.

EDWARD WILLIAM MACKENZIE HUGHES.
